(57) **CLAIM**

The ornamental design for a combined headgear net with carrying pouch, as shown and described.

DESCRIPTION

FIG. 1 is a top perspective view of a combined headgear net with carrying pouch showing my new design, the headgear net shown deployed from its carrying pouch;

FIG. 2 is a front elevational view thereof;

FIG. 3 is a left side elevational view thereof;

FIG. 4 is a bottom plan view thereof;

FIG. 5 is a right side rear elevational view thereof;

FIG. 6 is a top plan view thereof;

FIG. 7 is a rear elevational view thereof;

FIG. 8 is a front elevational view of the carrying pouch of FIG. 1 with the mosquito net folded therein;

FIG. 9 is a top plan view thereof;

FIG. 10 is a right side elevational view thereof;

FIG. 11 is a left side elevational view thereof;

FIG. 12 is a rear elevational view thereof; and,

FIG. 13 is a bottom plan view thereof.

The person shown in broken lines in FIG. 1 is for illustrative purposes only and forms no part of the design.
